UNITED STATES PATENT OFFICE.

JOSEPH WILLARD GAMBLE, OF PHILADELPHIA, PENNSYLVANIA, ASSIGNOR TO JOSEPH S. LOVERING WHARTON, WILLIAM S. HALLOWELL, AND JOHN C. JONES, DOING BUSINESS UNDER THE FIRM NAME OF HARRISON SAFETY BOILER WORKS, OF PHILADELPHIA, PENNSYLVANIA.

COMBINED HEATER AND SEPARATOR.

No. 926,108.

Specification of Letters Patent.

Patented June 29, 1909.

Application filed May 6, 1908. Serial No. 431,271.

To all whom it may concern:

Be it known that I, JOSEPH WILLARD GAMBLE, a citizen of the United States, and resident of and whose post-office address is No. 5 3251 North Sixteenth street, city of Philadelphia, county of Philadelphia, and State of Pennsylvania, have invented certain new and useful Improvements in Combined Heaters and Separators, of which the following is, taken in connection with the accompanying drawings, a full, clear, and concise description.

My invention comprehends a combined heater and separator, having means for controlling the admission of the exhaust steam passing through the separator to the heater.

My invention further comprehends certain hand-controlled valve mechanism for controlling the overflow from the heater, all of 20 which will be fully understood from the following specification.

Referring to the accompanying drawings, in which like reference numerals indicate like parts throughout the several views, Figure 1 is a view of my improved combined heater and separator partly broken away to show the interior construction of the intermediate valve. Fig. 2 is a top plan view thereof.

Referring to the figures, 1— indicates a heater having attached thereto, or made part thereof, a separator 2—.

3— indicates an exhaust steam supply connection; 4— an exhaust from the separator 35 2—.

The separator 2— is provided with an interiorly vertically arranged baffle 5— provided with suitable ribs or corrugations 6—. The baffle 5— has side openings or 40 ports 7— providing passageways from the inlet 3— around the baffle to the heater 1— or exhaust 4—.

Intermediate the heater 1— and separator 2— is arranged a passage or opening 45 8— through which the steam passes to enter the heater. The passage of the steam through the opening or passageway 8— is controlled by a cut out or slide valve. This cut out or slide valve comprises two 50 plates 9— and 10— having attached thereto screw threaded studs or projections 11— and 12— through which the spindle 13— rotates; the periphery of the

spindle 13— is provided with right and left hand threads 14— and 15—.

16— indicates a support or a projection for supporting the spindle 13—.

At the end of the spindle 13— I provide a crank 17— carrying a crank handle 18—. It will be readily seen that upon the rotation of the crank 17— the spindle 13— through the right and left hand threads described will gradually move the cut out plates 9— and 10— toward or away from one another as the case may be, and enlarging or contracting the opening from the separator to the heater, thus increasing or diminishing the steam supply thereto.

19— indicates the overflow chamber and 20— the passageway from the heater thereto. This passageway is provided with a controlling valve 21— actuated by a hand wheel 22—.

23— indicates a gage of ordinary construction.

24— indicates a vent or exhaust outlet from the heater to the atmosphere, and 25— a drip pipe connector connecting the separator and the overflow chamber 19—.

I am aware that it is old in the art to employ a valve in the exhaust inlet to the heater, but no valve to my knowledge has been employed in a combined heater and separator, intermediate the two for cutting out the heater to divert the treated steam as to a heating system or the like.

Where I have used the words "unitary structure," I mean that both the heater and separator form part of the same structural unit.

It will be apparent that by the employment of the two valves, 9— and 21—, I am enabled to wholly and effectively cut out the heater when it is desired to clean or otherwise repair the interior thereof and accomplish such cleaning or repair with safety, free from interference from any exhaust steam entering the heater from separator, either through passageway 8— or through drip connection 25— and passageway 20—.

Having thus described my invention, what I claim herein and desire to protect by Letters Patent is:—

1. A unitary structure comprising a heater; a separator provided with a baffle;

- and means intermediate the separator and the heater for controlling the passage of steam between the separator and the heater.
2. A unitary structure comprising a heater; a separator provided with a baffle; a valve controlled outlet from the separator to the heater; and an auxiliary outlet from the separator beyond the baffle.
3. A unitary structure comprising a heater; a separator provided with a baffle; an outlet from the separator to the heater; an auxiliary outlet from the separator beyond the baffle; and means for controlling the outlet between the separator and the heater.
4. A unitary structure comprising a heater; a separator provided with a baffle; an outlet from the separator to the heater; means for controlling the outlet between the separator and the heater; an auxiliary outlet from the separator; an overflow from the heater; a passageway connecting the separator and the overflow and means intermediate the heater and the passageway from the separator to overflow for controlling the overflow from the heater.
5. A unitary structure comprising a heater; a separator provided with a baffle; and a valve intermediate the separator and the heater comprising two plates moving in opposite directions.
6. The combination of a heater; a separator; a valve controlled passage from the separator to the heater; an overflow from the heater; a passage between the separator and the overflow, and means intermediate the heater and the latter passage for controlling the overflow from the heater.
7. A unitary structure comprising a heater; a separator; a baffle in said separator; means intermediate said separator and heater for controlling communication between the same; an overflow from heater; a passage between separator and overflow; and means intermediate the heater and passage from separator for controlling said overflow.
8. A unitary structure comprising a heater; a separator; means intermediate said separator and heater for controlling communication between the same; an overflow from heater; a passage between separator and overflow; and means intermediate the heater and passage from separator for controlling said overflow.
9. A unitary structure comprising a heater; a separator shell attached directly thereto; an opening between the heater and said separator; means for controlling said opening; an overflow from heater; a passage connecting the separator with the overflow; and means intermediate said heater and passage from separator for controlling the overflow.
10. The combination of a heater having an overflow chamber; a separator; communicating passageways between the separator, overflow and heater; and valves for controlling the passageways from the separator to the heater and from the heater to the overflow chamber.
11. The combination of a heater and separator; a valve controlled passage from the separator to the heater; an auxiliary outlet from the separator; an overflow from the heater; a passage between the separator and the overflow; and means intermediate the heater and the latter passage for controlling the overflow from the heater.
12. The combination of a heater having an overflow chamber and a separator; a valve intermediate the heater and separator; an auxiliary outlet for said separator; a drip connection for said separator connecting it to the overflow chamber, and a passageway connecting the heater with the overflow chamber, and means for cutting the heater out of communication with both overflow chamber and separator.

Signed at Philadelphia in the county of Philadelphia and State of Pennsylvania this 30th day of April 1908.

JOSEPH WILLARD GAMBLE.
